Primary Examiner — John Windmuller*Assistant Examiner* — Steven J Czyz(74) *Attorney, Agent, or Firm* — ScienBiziP, P.C.(57) **CLAIM**

The ornamental design for an earphones box, as shown and described.

DESCRIPTION

FIG. 1 is a top front perspective view of an earphones box showing the new claimed design;

FIG. 2 is a bottom rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a perspective view of the earphones box shown in an open position.

The broken lines depict portions of the article and environment that form no part of the claimed design.

1 Claim, 9 Drawing Sheets(56)
